[57] **CLAIM**

The ornamental design for a culinary press for garlic or similar materials, as shown and described.

DESCRIPTION

FIG. 1 is a perspective view from above and side of a culinary press for garlic or similar materials showing my new design;

FIG. 2 is a bottom plan view thereof;

FIG. 3 is an elevation taken from either side having the recess therein;

FIG. 4 is an elevation taken from either side that is non-recessed; and

FIG. 5 is an elevation thereof with the cap in an alternative position.

FIG. 1.

FIG. 3.

FIG. 4.

FIG. 2

FIG. 5.
